UNITED STATES PATENT OFFICE.

FREDERICK L. FOX, OF WASHINGTON, DISTRICT OF COLUMBIA, ASSIGNOR OF ONE-FOURTH TO HENRY I. MEADER, ONE-FOURTH TO DONALD B. PHILLIPS, AND ONE-FOURTH TO CHARLES D. DAVIS, OF WASHINGTON, DISTRICT OF COLUMBIA.

BOAT.

1,389,865.

Specification of Letters Patent.

Patented Sept. 6, 1921.

Application filed April 17, 1916, Serial No. 91,650. Renewed May 25, 1921. Serial No. 472,577.

To all whom it may concern:

Be it known that I, FREDERICK L. FOX, a citizen of the United States of America, and a resident of Washington, District of Columbia, have invented certain new and useful Improvements in Boats, of which the following is a full and clear specification.

This invention has relation to that type of boats in which the speed is increased by delivering and confining under the bottom of the boat a layer or film of air to thereby tend to raise the boat out of the water and cause it to travel partially on air; and one of the objects of my invention is to provide air-gathering flues which will compress the air before it is delivered under the bottom, to thereby materially increase the buoyant capacity of the air, as more fully hereinafter set forth.

20 A further object of my invention is to provide the boat with an outrigger pontoon arrangement to insure proper balancing of the boat, these pontoons being so arranged that as the main hull is raised from the water by increase in speed, the pontoons will be lifted entirely out of contact with the water, thereby greatly decreasing water drag.

30 A still further object of my invention is to provide each of these pontoons with means whereby a layer of air is delivered under the bottom thereof in the same manner as with the main hull, thereby still further increasing the buoyancy of the boat.

35 Another object of my invention is to utilize the means for connecting the pontoons to the main hull to act as air-planes and thus still further increase the buoyancy of the boat, as more fully hereinafter set forth.

40 A further object of the invention is to employ both an air rudder and a marine rudder and to connect them up to a single steering mechanism, so that they shall be operable in unison; and a further important feature of 45 my invention is the provision of means whereby the marine rudder may be hoisted out of the water entirely when the boat has attained a speed sufficient to enable it to be steered entirely by the air rudder, thereby 50 materially reducing the water drag on the boat.

In the drawings—

Figure 1 is a top plan view illustrating a

boat embodying my novel features in their preferred form;

55

Fig. 2 is a side elevation thereof;

Fig. 3 is a vertical longitudinal section of the boat, the propelling means being removed;

Fig. 4 is a transverse section on the line 60 4—4 of Fig. 3;

Fig. 5 is a section on the line 5—5 of Fig. 1;

Fig. 6 is a vertical longitudinal section taken through one of the pontoons;

65

Fig. 7 is a transverse section on the line 7—7 of Fig. 3;

Fig. 8 is a detail side elevation of the stern, showing more particularly the means for manipulating the marine rudder;

70

Fig. 9 is a section on the line 9—9 of Fig. 8;

Fig. 10 is a perspective view of the mechanism for manipulating the air rudder and the marine rudder;

75

Fig. 11 is a detail vertical section taken through the upper end of the rudder post; and

Fig. 12 is a plan view of one of the pontoons and its connected air-plane detached.

80

Referring to the drawings annexed by reference characters, *a* designates an air flue inclining downwardly and rearwardly through the bow end of the main hull, the upper end of this flue being shaped to form 85 a forwardly-facing funnel *b* and the lower end of the flue being contracted to form a nozzle *c* pointing directly rearwardly under the main portion *d* of the bottom of the boat. The flue *a* and funnel *b* and nozzle *c* extend approximately the full width of the boat, and the nozzle *c* is smaller in area than the entrance end of the flue, so that the air 90 that is gathered by the funnel *b* is compressed during its passage through the flue and before it is ejected under the bottom of the boat in a comparatively thin layer or body.

95 The air is confined under the bottom of the boat by depending side runners *e* arranged at the side edges of the boat. The air-gathering and compressing flue above described is arranged forward of the cock-pit *f*, and it is desirable that this air-gathering and compressing device shall be duplicated at a 100 point back of the cock-pit. This second air- 105

compressing flue is shown at *a'*, *b'* and *c'*, this rear flue being arranged to eject the air it compresses under the rear part *d'* of the bottom, this second air cavity (formed by the bottom part *d'* and the rear portions of the runners *e*) being open at its rear end to permit free escape of the air. It is desirable to have the forward cavity (formed by the part *d* of the bottom and the runners *e*) 5 tapered toward its rear end to thus still further compress the air as the boat advances, and, to accomplish this, I incline the rear end of the part *d* of the bottom downwardly and terminate it at the point where the rear 10 air-compressing flue discharges the air under the bottom part *d'*, this rear extremity of the bottom part *d* riding slightly above the lower edges of the runners, so as to avoid forcing the trapped air laterally under the 15 runners. It is desirable also that the forward bottom part *d* shall be formed virtually of a continuation of the top wall of the forward flue *a*, these two parts being merged into each other on a curved line, 20 thereby reducing air friction to a minimum. The same is done with the rear part *d'* of the bottom and the top wall of the rear flue. 25 With the arrangement above described, it will be observed that the feature of greatest 30 importance is the compressing of the air while it is passing through the hull of the boat and before it is delivered under the boat, whereby the buoyant capacity of the air is greatly increased. It will be under- 35 stood that the funnel delivers, practically entirely across the bottom of the boat, a continuous stream or layer of air under pressure, which layer or stream meets the water, as the boat progresses, at the lower edge of 40 the flat nozzle. By thus previously compressing the air, the thinning of the air layer by the compacting effect of the water will be materially reduced, thereby keeping the water away from the bottom of the hull 45 for a longer period than would be the case if the air were delivered under the boat in a non-compressed state, whereby air-friction is substituted for hull-friction to a material extent. Another feature of import- 50 ance is that the nozzle portions *a*, *a'* of the flues have their exit ends directed directly backwardly and not downwardly, whereby the delivery of the compressed air under the boat is materially facilitated. 55 Any suitable air propelling mechanism may be employed. I have found in practice that the following arrangement is advantageous:

Secured upon the deck of the main hull 60 and extending in parallelism is a pair of rails 31; each having a plurality of openings 32 arranged therein and adapted to receive bolts 33 by which the motor mounting, generally indicated at 34, may be adjustably 65 connected to the rails. This motor mount-

ing may be of any preferred form but generally consists of a double A-frame, the legs of which on each side are connected by a track engaging member 35 and the frames are braced by diagonal struts 36 also adjustably connected to the rails, as shown. By this means of adjustment, the motor which is indicated at 37 may be shifted toward the bow or stern of the boat, as is found expedient and the weight of the operator and 70 passengers thus properly equalized, so as to prevent unevenness of travel. The adjustment of the motor also eliminates depression of the bow caused from thrust of the motor. As will be seen, the motor, which has only 80 been generally shown, is connected to the propeller shaft 38 by means of a chain 39, while the shaft 38 carries the usual air propeller 40 and a starting crank 41.

Connected to the sides of the hull of the 85 boat at the rear end of the boat is a pair of water-tight pontoon hulls *g*, supported away from the main hull by wings *h* rigidly connecting the main hull to the pontoons. The wings *h* are connected to the main hull at a 90 point high enough to prevent them ever resting on the surface of the water, and, in order that these wings may act as air-planes and thus assist in lifting the boat out of the water, I shape them, in longitudinal section, 95 in the same manner as an approved aeroplane wing or plane, as clearly shown in Fig. 5.

Each pontoon hull is provided with an air-compressing flue *i* similar in shape and function to the air-compressing flues in the main hull, so that, while the pontoons are riding on the water, a layer or film of compressed air will be injected under each pontoon, thereby materially adding to the buoyancy 100 of the boat. It will be observed from Figs. 2 and 7 that the pontoons have their bottoms located at a point above the plane of the bottom of the main hull, so that, when the boat attains a sufficient speed to lift it out 105 of the water a predetermined extent, the pontoons will be entirely out of contact with the surface of the water, whereby the water drag on the boat is greatly diminished. It will be observed, however, that even when 110 the pontoons are thus lifted entirely away from the surface of the water, they still serve 115 to assist in balancing the boat.

Any suitable means may be employed to rigidly connect the pontoons and wing 120 planes to the main hull, but I prefer making this rigid connection by means of parallel bars *j* affixed rigidly to the decks of the pontoon hulls and extending horizontally through the wing plane structures and having their ends rigidly fastened to the deck of the main hull. I prefer connecting these rods to the main hull by having their ends inserted in open-ended metal tubes *k* fastened in transverse grooves in the deck of 125 130

the main hull. The rods are conveniently secured removably in these tubes by vertical bolts *l* passing down through the tubes and through the inclosed ends of the rods. This 5 manner of connecting the pontoons and wing planes to the main hull is advantageous in view of its simplicity and rigidity, and also because by simply removing the bolts *l* each pontoon with its connected wing 10 plane may be detached from the hull for the sake of compactness in shipping and storing the boat.

For steering the boat, I provide an air rudder *m* at the bow and a water rudder *n* 15 at the stern, and I manipulate these two rudders in unison from a single steering shaft *o* mounted preferably in the cock-pit. The air rudder is connected to the steering shaft by a suitable cable *p* and the marine 20 rudder is connected to the steering shaft by a suitable cable *q*, these cables being supported on a suitable pulley arrangement in the hull. The cable *q* is wound around a grooved wheel *r* attached to the upper end 25 of the rudder post *s*, this post being journaled in a vertical bearing tube *t* supported rigidly at the stern of the boat.

The marine rudder is pivoted at its upper forward end on a pivot *u* mounted between 30 the forward ends of a pair of arms *v* connected rigidly to the lower end of the rudder post. These arms closely hug the rudder blade and serve to resist lateral thrust on the rudder. The pivotal connection of the rudder 35 blade with the arms *v* enables it to be hoisted out of the water, so that when sufficient speed is attained to enable the boat to be steered by the air rudder alone, the drag of the water rudder may be entirely 40 eliminated. As will be seen, the marine rudder and its supporting parts are so arranged that, when the rudder blade is raised, none of the water steering parts have contact with the water.

45 The rudder may be raised and held up in any suitable manner, as is obvious. I prefer lifting the same by means of a cable *w* attached to the upper edge of the blade and passing through a tube *x* extending through 50 pulley *r*, the upper end of this tube terminating directly in line with the axial center of the rudder post, so that by pulling forward on the cable *w*, the blade may be readily lifted out of the water at whatever angle it 55 may be adjusted to at the time. The forward end of the cable *w* is carried to the cockpit where it is attached to a lever *y*, and this lever is preferably so mounted that when it is swung forwardly and downwardly it will 60 carry the point of connection of the cable *w* to the lever beyond center, so that the backward pull on the cable will cause the lever to be locked in elevated position. Any other suitable means, however, may be employed 65 for holding the rudder up out of the water.

It will be observed that the bottom sections of the main hull together with the sides and top boards or plates thereof and the air flues *a* and *a'* convert the main hull into virtually a series or row of three separate pontoons. 70 The advantage of this is that the puncturing or crushing of the hull at any one point will not sink the boat.

Having thus described my invention, what I claim is:

75 1. A boat having a channel or cavity formed on its bottom and provided with a flue extending through its hull and communicating at its lower end with the forward end of said cavity, this flue being provided at its upper forward end with an air-gathering funnel, said lower discharge end of the flue being restricted in area as compared with the intake end of the flue to thereby compress the air before it is delivered under the 85 boat.

2. A boat having a channel or cavity formed on its bottom and provided with a flue extending through its hull and communicating at its lower end with the forward end 90 of said cavity, this flue being provided at its upper forward end with an air-gathering funnel, said lower discharge end of the flue being restricted in area as compared with the intake end of the flue to thereby compress 95 the air before it is delivered under the boat, the exit end of the flue being in the form of a nozzle facing horizontally rearwardly.

3. A boat having a plurality of cavities 100 formed under its bottom and provided with an air flue for each cavity, each of these air flues extending through the hull of the boat and connected to the forward end of the cavity, the lower exit end of the flue being restricted in area as compared with the intake end to thereby preliminarily compress 105 the air before it is delivered under the boat.

4. In a boat, a main hull; outrigger hulls; and means connecting the main and outrigger 110 hulls, said means being adapted to be acted upon by the air in the movement of the boat to tend to lift the boat out of the water.

5. In combination with a main hull, outrigger or pontoon hulls; and means connecting these pontoon hulls with the main hull, 115 said means consisting of air-planes or wings connecting the hull to the pontoon above the load water line.

6. The combination with a main hull, of a pair of outrigger or pontoon hulls, each of 120 which is provided with an air flue extending through the hull and adapted to deliver a body of air underneath the bottom of the hull, for the purpose set forth.

7. The combination with a main hull, of a 125 pair of pontoon or outrigger hulls; and means connecting the pontoon hulls to the main hull, said means embodying rods affixed to the pontoon hulls and to the deck of the main hull, the connection of the rods 130

to the main hull being separable, said main hull being provided with transverse grooves for the reception of said rods, for the purpose set forth.

5 8. The combination with a boat of the type set forth, of a steering means therefor embodying an air rudder at the bow and a marine rudder at the stern; and means for simultaneously manipulating these rudders, so 10 that they shall coöperate with each other; and means for raising the marine rudder out of the water to relieve the boat of the drag of the marine rudder when the boat has at-

tained sufficient speed to be guided by the air rudder alone.

9. The combination with a boat of the type set forth, of steering means therefor embodying an air rudder and a marine rudder; and means for raising and holding the marine rudder out of the water to thereby relieve the boat of the drag of the rudder after it has attained sufficient speed to be guided by the air rudder alone. 15 20

In testimony whereof I hereunto affix my signature.

FREDERICK L. FOX.
